FEED BINDER

Original Filed May 18, 1926

Inventor
D. A. Kidwell.

By *Frank Murphy Jr.* Attorney

UNITED STATES PATENT OFFICE

DAVID A. KIDWELL, OF IMA, NEW MEXICO

FEED BINDER.

Application filed May 18, 1926, Serial No. 109,916. Renewed January 23, 1930.

This invention relates to a binder or holder for a sheaf of feed for cattle and stock and it is generally aimed to provide a novel, more efficient and durable construction.

Another object is to provide such a device wherein the chain will be automatically locked in its different positions of adjustment, simply by direct movement as contrasted with lateral movement of the chain and also a construction which may be used in minimum space as in the corner of a room or bottom of a manger, holding the feed so that it cannot be unduly loosened or destroyed, necessitating the eating thereof substantially completely and without loss.

Additional objects and advantages will become apparent from a consideration of the description following taken in connection with accompanying drawings illustrating an operative embodiment.

In said drawings:—

Figure 1 is a view illustrating the device in elevation and with the chain in open position;

Figure 2 is an end elevation, and

Figure 3 is a horizontal sectional view taken on the line 3—3 of Figure 1 but with the chain in locked position.

Referring specifically to the drawings, a locking bar of appropriate size is provided at 10 which may be of cast metal although it may be of malleable material or otherwise as preferred. This bar has suitable slots as at 11 and 12, the latter preferably being elongated and accommodating bolts or other fastenings 13 secured through a suitable support, indicated at 14, and provided with nuts 15 to secure the bar 10 in position. The support 14 may be the bar of a manger or a post located in any desired position, and the purpose of the bolts is to detachably and rigidly secure the device in place so that it cannot be dislodged by stock or cattle. It will be apparent that instead of bolts and nuts, long screws may be used for the purposes stated.

At one end of the said bar 10, a loop or eyelet is provided as at 16 to which one end of a binder chain 17 may be secured, as by means of any suitable form of snap hook 18, or the like. Said snap hook may be of the type

illustrated, having a closure spring 19, or may be of any other type found desirable, and has a swivel link 20 secured to one end of the chain 17. The chain 17 is preferably metallic and of any suitable form, and has a cross-bar 55 21 with an ear 22 secured to the end of the chain remote from the hook 18.

At the other end of the bar 10, a guide roller 23 is provided, being journaled on a pin or post 24 and the chain 17 is adapted to surround a sheaf of feed, such for instance as oats, Kaffir, cane, sudan grass, or other material in a bundle, it being immaterial of course what material the device is used in connection with. The end of the bar 10 adjacent said roller is deflected toward the chain side and bifurcated and in the bifurcation has a locking member 25 disposed, and pivoted at 26 on a rod or bolt secured to that end. In addition, a coil spring 27 surrounds the rod or bolt 26, having one end abutting the bar 10 and the other end abutting the locking member 25, so that the latter will always remain in contact with the roller 23 and be urged in a direction toward the same. The free end of the locking member terminates in a point or tooth as at 28, adapted to directly engage the opening of any link of the chain 17.

Along each side of the bar, it is provided with a flange 29, serrated at 30, so as to engage the feed material, with a view to preventing movement of the bar and binder about the same. The flanges 30 are also extended on the opposite side of the bar as at 31, to strengthen the same.

The pin or bolt 24 is carried by ears 32 forming extensions of the flanges 29.

In the use, the bar is usually first fastened in position as by means of the bolts 13 and the chain 17 is unfastened at the snap hook 18. Thereafter the bundle of feed, such as oats, Kaffir, corn, sudan grass, or other material, is placed against the bar and the snap hook resecured to the loop 16. The chain may then be tightened by drawing the cross bar towards the operator with the locking member 25 automatically engaging in the opening of each of the links of chain 17 as such chain is drawn taut. The chain thus cannot slip and the feed will be secured tightly in place and

will also be automatically secured in place. Should it be necessary to disengage the chain for any reason, it may be automatically disengaged from the locking member simply by 5 pulling the chain slightly forward and then giving a slight lateral movement.

Various changes may be resorted to provided they fall within the spirit and scope of the invention.

10 I claim as my invention:—

A binder device of the class described comprising a bar having spaced flanges, said flanges being serrated to engage a bundle, a chain secured to one end of the bar, said 15 flanges being extended at the other end of the bar, a roller journaled between the extended flanges and over which said chain passes, the bar being extended beyond said extended flanges, a locking member pivoted to the ex- 20 tended portion of the bar outwardly of the roller, and a spring urging said locking member into engagement with the roller, whereby the locking member will constantly engage the chain and automatically engage it in the 25 different adjusted positions of the latter.

In testimony whereof I affix my signature.

DAVID A. KIDWELL.
